New Orleans, La. 70115

Filed July 20, 1970, Ser. No. 44,035

Term of patent 14 years

Int. Cl. D2—03

U.S. CL. D2—243

FIG. 1 is a front elevational view of the neckwear accessory showing my new design;

FIG. 2 is a side elevational view thereof, the side opposite being a mirror image;

FIG. 3 is a second embodiment of the design of FIG. 1, the design in a side elevational view being substantially similar to FIG. 2, the leaves being substantially flat and lying in substantially the same plane as the flat backing member.

I claim:

The ornamental design for a neckwear accessory, as shown and described.
